DESIGN.

A. B. CAMERON.
ORNAMENTAL PANEL.

No. 19,473.

Patented Dec. 10, 1889

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of Design No. 19,473, dated December 10, 1889.

Application filed November 12, 1889. Serial No. 330,074. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to an ornamental panel having a configuration hereinafter set forth.

Upon the surface of the panel is a rectangular elevation A. Upon said elevation appear grooves or channels, as B, extending from the center C of said elevation to the edges thereof. Also upon said elevation appear

grooves or channels D E F G, which extend between and join the middle points of the sides of said elevation A. The whole of the elevation A thus appears to be divided into a number of irregularly-shaped geometrical figures, the edges of which may appear stepped, as shown in the photograph.

I claim—

The design for an ornamental panel, substantially as herein shown and described.

ALLAN B. CAMERON.
